UNITED STATES PATENT OFFICE.

ELMER R. CORWIN, OF CHICAGO, ILLINOIS, ASSIGNOR TO MONARCH TELEPHONE MANUFACTURING CO., A CORPORATION OF ILLINOIS.

TELEPHONE-EXCHANGE SYSTEM.

No. 888,874.

Specification of Letters Patent.

Patented May 26, 1908.

Application filed October 1, 1906. Serial No. 337,029.

To all whom it may concern:

Be it known that I, ELMER R. CORWIN, a citizen of the United States, residing at Chicago, in the county of Cook and State of Illinois, have invented a certain new and useful Improvement in Telephone-Exchange Systems, of which the following is a full, clear, concise, and exact description, reference being had to the accompanying drawings, forming a part of this specification.

My invention relates to telephone exchange practice, and has for its object the provision of improved circuits and apparatus whereby telephone exchange practice may be simplified and improved.

My invention is serviceable in connection with switch-boards of the simple or multiple type, and one feature of the invention is of particular service in connection with multiple switch-boards.

My invention will more fully appear by reference to the accompanying drawing, showing its preferred embodiment as applied to multiple switch-boards, and will be pointed out in the claims.

In the drawing there are indicated two of many sub-stations, A, B, which, in this instance, are subscribers' stations, each having a transmitter 1, a receiver 2, a call bell 3, a switch-hook 4, a condenser 5, and an impedance coil 6, together with suitable contacts and circuit connections whereby, when the telephone receivers are upon their switch-hooks, the bells 3, together with the condensers 5, are bridged across the sides of the telephone lines 7, 8, and whereby, when the telephone receivers are removed from their hooks, the bridges including signaling bells are opened and the transmitters are thrown into conductive connection with the lines, whereby battery may be fed therethrough through the impedance coil 6, and whereby these currents may be impressed upon the lines at the sub-stations at the transmitters or

may be received at the receivers. I do not wish, however, to be limited to the precise sub-station circuits indicated. The limbs 7, 8 of the telephone lines are, in multiple switch-board practice, multiplied to sleeve contacts or thimbles 9 and ring contacts 10, respectively, of multiple spring jacks, though the invention may be useful in connection with switch-boards that are not multiple switch-

boards, in which case but one jack need be supplied to a line. In multiple switch-board practice, one of the jacks may act as an answering jack, the answering jacks, as is understood, being suitably distributed among the different sections of the switch-board, the multiple jacks being multiplied to the several sections of the switch-board, which grouping arrangement, or any other preferred grouping, is well understood.

In the embodiment of the invention shown, the line relays 11 have their windings desirably permanently included in extensions of the conductors 8 and in connection with the common battery 12, the circuit of this battery desirably having one of its poles permanently connected with one side of each of the subscribers' circuits through the relays 11 and the other pole connected with the other sides of the subscribers' circuits through the impedance device 13. When a subscriber removes his telephone, the line relay 11 becomes energized, whereby a signal through the line signal device 14 of the calling subscriber may be closed by way of a line relay switch 15 and its alternate contact 15'. The circuit of each line indicator also includes the armature switch 16 and the normally engaged back contact 16' of the cut-off relay 17 corresponding to the signal device 14. When a cut-off or line signal-effacing relay 17 is energized, the circuit of the corresponding line signal is opened at 16', whereby the line signal is effaced. This cut-off relay has its circuit closed by the co-operation of a plug and the corresponding jack into which said plug is inserted. After the circuit of the cut-off relay is thus closed, said circuit is under the control of the sub-station of the corresponding telephone line. For this purpose, the circuit of each cut-off relay desirably includes the armature switch 18, that is connected with one terminal of the cut-off relay winding.

When a plug, such as plug 19 is inserted into a jack, the tip 20 of the plug engages a jack spring 21 of the jack into which the plug is inserted, which jack spring is connected with the back contacts of the armature switches 15 and 18, and, by reason of its connection with the back contact, the armature switch 18 is included in the local circuit that is initially established for the cut-off relay 17,

this local circuit, as now established, being traceable from the upper pole of battery 12 to the armature switch 15, the alternate contact 15² of the latter armature switch, the winding of relay 17, which is preferably of large resistance, say one thousand ohms, the armature switch 18, its normal contact, the jack spring 21, the tip 20 of the engaging plug, the conductor including the clearing-out or supervisory signal 22 (which signal is not operated, for the circuit now being traced is only momentarily established), the body contact 23¹ of the plug 19, thence to the remaining terminal of the battery 12 by way of the impedance coil 13. If the plug 23 were the plug inserted, the circuit traced would be similar. When circuit is thus closed through a cut-off relay, the armature switch 18 is attracted, thereby interrupting this circuit, but inasmuch as this armature switch is attracted very quickly, it has time to engage its alternate contact 24 before the cut-off relay is de-energized, whereupon a second local circuit is established to maintain the cut-off relay energized until the corresponding switch-hook or switching device is operated at the corresponding sub-station to effect an opening of this circuit of the cut-off relay. This second local circuit for the cut-off relay may be traced from the upper pole of the battery 12, through the armature switch 15, the contact 15² engaging said armature switch, the winding of the cut-off relay 17, the armature switch 18, the alternate contact 24, to the remaining terminal of the battery 12. It will be seen that this circuit last traced includes none of the apparatus under the operator's control, but that it is exclusively controlled by apparatus governed from the sub-station, in this particular instance, the armature switch of line relay 11 and the engaging contact 15². As soon as this armature switch 15 is released, which happens when a subscriber restores his telephone upon its switch-hook, thereby opening the circuit of the line relay 11, the circuit of the corresponding cut-off relay is broken at 15² without the aid of the operator. By making the cut-off relay of high resistance, a minimum quantity of current is required to maintain its energization during an established connection. As hitherto stated, either plug 19 or 23 has similar effect upon the cut-off relay circuits corresponding to the jacks with which said plugs are engaged, and the parts upon the right hand of the drawing that are similar to the parts upon the left hand of the drawing are given similar characters of reference, with the exception that the supervisory signal upon the right hand of the cord circuit is marked 25. The clearing-out or supervisory signals 22, 25 are desirably in the form of small incandescent lamps, though I do not wish to be limited to the character of signaling devices employed as clearing-out or supervisory signals, and while

I prefer two signals for each cord circuit—one corresponding to the calling subscriber and the other corresponding to the called subscriber—I do not wish to be limited to the number of such signals employed.

The operator's listening key is shown at 26, 26 and is of a well known type.

Each supervisory or disconnect signal circuit has the signal included therein normally disconnected from battery, that is, it is disconnected from battery while the cord circuit is out of service, which is another feature of my invention. Battery is only connected with these clearing-out or supervisory signals when the cord circuit is in use. In the embodiment of the invention shown, the supervisory signal circuits include each the tip of a plug, the non-talking strand of the cord circuit connected with said plug, the talking strand connected with the body contact 23¹ and the supervisory signal connected between said strands, the body contact or thimble of the engaged jack, the impedance 13, the battery 12, the armature switch 15, the back contact of said armature switch (for the clearing-out or supervisory signal circuits are only closed when the line relays are deenergized, back to the tip 20. It is apparent that the supervisory signal circuits when closed are opened upon the withdrawal of the corresponding plugs, by reason of the separation of the elements 20, 21. Either of the plugs 19, 23, in multiple switch-board practice, may, in accordance with the preferred embodiment of my invention, constitute a testing plug.

The operator's telephone set is provided with an induction coil for testing purposes, which induction coil has a ground connection effected at 27 therewith, a half of the primary 28 being upon each side of the connection 27. The terminals of this primary reside in alternate contacts of the operator's key 26, one-half of the primary being connected with the tip 20 of the plug 19, while the other half of the primary is connected with the tip 20 of the plug 23 when the operator's key is operated to cut her telephone into circuit, the half of the primary that is connected with the tip 20 of plug 19 being included in the test circuit when the plug 19 is used as a testing plug, while the other half of the primary is included in the test circuit when the plug 23 is used as a testing plug. Assuming that either plug is used as a test plug, and assuming that a jack that is being tested is associated with the line in a jack of which a plug is elsewhere inserted, the test circuit will be as follows: From the ground at 27, through one-half or the other of the primary of the operator's testing outfit, according to the plug that is being used, to the tip of the testing plug, the thimble 9 of the tested jack, the body contact 23¹ of the plug inserted in another jack belonging

to the group that contains the jack being tested, the supervisory signal corresponding to the other plug, to the tip of said other plug, the spring contact 21 engaged by the latter tip, the armature switch 15 and its normal contact (now assuming that the line is open at the sub-station), to one pole of the battery 12; through said battery, to ground, thence back to the ground at 27. If the line 5 is closed at the sub-station, the test circuit will be traced from the ground at 27, through a half of the primary 28 of the operator's testing outfit, the tip 20 of the testing plug, the thimble 9 of the jack being tested, 10 through the sub-station, the line relay 11, through the battery 12, to ground. The secondary 28¹ is included in circuit with the operator's receiver, the testing current being induced in the operator's receiver circuit. 15 20 It will be seen that the testing battery current is normally removed from the idle cord circuits by my improved circuit arrangement.

Another feature of my invention resides in 25 the interchangeability of the plugs of each cord circuit, as I may use either plug as a connecting and testing plug and either plug as an answering plug. To this end, I associate a ringing key 29 with each of the plugs, 30 so that the ringing generator 30 may be thrown into connection with either of the plugs. Each of the ringing keys 29 breaks the cord circuit when it is operated, so that the calling generator 30 is limited to circuit 35 relation with but one of the plugs. The advantage of this feature of my invention resides in the fact that if a called subscriber should become a calling subscriber before the plug is removed from his jack, the mate 40 to said plug may be used in testing the newly called for subscriber, and if said subscriber's line be found idle, said latter plug may be inserted into the newly called subscriber's jack and said newly called subscriber may be rung by the operation of the 45 corresponding ringing key.

It is obvious that changes may readily be made in the preferred embodiment of my invention, without departing from the spirit 50 thereof, and I do not, therefore, wish to be limited to the precise constructions and arrangements shown, but,

Having thus described my invention, I claim as new and desire to secure by Letters- 55 Patent:

1. A telephone exchange system including telephone lines extending to an exchange and there provided with jacks, cord circuits for uniting lines in conversation, disconnect signals associated with the cord circuits, battery for effecting the operation of the disconnect signals and normally disconnected from the cord circuits, circuits for the disconnect signals, including said jack contacts, plug contacts for engaging said jack contacts, and
2. A telephone exchange system including the supervisory or disconnect signals, which conductors are normally disconnected from said battery, —line relays for the telephone lines, and an armature switch for each of said line relays, each controlling the continuity of the corresponding disconnect signal circuit. 70
3. A telephone exchange system including telephone lines extending to an exchange and there provided with jacks, cord circuits for uniting lines in conversation, disconnect signals associated with the cord circuits, battery for effecting the operation of the disconnect signals and normally disconnected from the cord circuit, circuits for the disconnect signals, —including said battery, jack contacts with which said battery is normally connected, plug contacts for engaging said jack contacts, and cord circuit conductors including the supervisory or disconnect signals, which 80 conductors are normally disconnected from said battery, —line relays for the telephone lines, and an armature switch for each of said line relays, each controlling the continuity of the corresponding disconnect signal circuit. 85
4. A telephone exchange system including telephone lines extending to an exchange and there provided with jacks, cord circuits for uniting telephone lines, line signal mechanism, cut-off or line signal-effacing relays normally in circuit connection with jacks of the corresponding line, said cut-off relays in establishing their alternative circuits opening their previously established circuits, circuit connections for the cord circuit plugs, whereby circuits through said cut-off relays may be momentarily closed, alternative circuits for 105 said cut-off relays established thereby, and line relays entering into the control of the latter circuits. 110
5. A telephone exchange system including telephone lines extending to an exchange and there provided with jacks, cord circuits for uniting telephone lines, line signal mechanism, cut-off or line signal-effacing relays, said cut-off relays in establishing their alternative 115 circuits opening their previously established 120 circuits. 125

circuits, circuit connections for the cord circuit plugs, whereby circuits through said cut-off relays may be momentarily closed, alternative circuits for said cut-off relays established thereby, and line relays entering into the control of the latter circuits.

6. A telephone exchange system including telephone lines extending to an exchange and there provided with jacks, cord circuits for
10 uniting telephone lines, line signal mechanism, cut-off or line signal-effacing relays normally in circuit connection with jacks of the corresponding lines, circuit connections for the cord circuit plugs, whereby circuits
15 through said cut-off relays may be momentarily closed, alternative circuits for said cut-off relays established thereby, line relays entering into the control of the latter circuits, and a battery for energizing said cut-off relays, said battery being normally disconnected from the cord circuits.

7. A telephone exchange system including telephone lines extending to an exchange and there provided with jacks, cord circuits
25 for uniting telephone lines, line signal mechanism, cut-off or line signal-effacing relays, circuit connections for the cord circuit plugs, whereby circuits through said cut-off relays may be momentarily closed, alternative 30 circuits for said cut-off relays established thereby, line relays entering into the control of the latter circuits, and a battery for energizing said cut-off relays, said battery being normally disconnected from the cord 35 circuits.

8. A telephone exchange system including telephone lines extending to an exchange and there provided with jacks, cord circuits for uniting telephone lines, line signal mechanism, cut-off or line signal-effacing relays normally in circuit connection with jacks of the corresponding line, said cut-off relays in establishing their alternative circuits opening their previously established circuits, circuit connections for the cord circuit plugs, whereby circuits through said cut-off relays may be momentarily closed, alternative circuits for said cut-off relays established thereby, line relays entering into the control of the latter circuits, and a battery for energizing said cut-off relays, said battery being normally disconnected from the cord circuits.

9. A telephone exchange system including
55 telephone lines extending to an exchange
and there provided with jacks, cord circuits
for uniting telephone lines, line signal mech-
anism, cut-off or line signal effacing relays,
said cut-off relays in establishing their
60 alternative circuits opening their previously
established circuits, circuit connections for
the cord circuit plugs, whereby circuits
through said cut-off relays may be momen-
tarily closed, alternative circuits for said
65 cut-off relays established thereby, line relays

entering into the control of the latter circuits, and a battery for energizing said cut-off relays, said battery being normally disconnected from the cord circuits.

10. A telephone exchange system including telephone lines extending to an exchange and there provided with jacks, cord circuits for uniting telephone lines, cut-off or line signal-effacing relays normally in circuit connection with jacks of the corresponding line, said cut-off relays in establishing their alternative circuits opening their previously established circuits, circuit connections for the cord circuit plugs, whereby circuits through said cut-off relays may be momentarily closed, alternative circuits for said cut-off relays established thereby, line relays entering into the control of the latter circuits, line signal devices, and circuits therefor establishable by the line relays and breakable by the cut-off relays.

11. A telephone exchange system including telephone lines extending to an exchange and there provided with jacks, cord circuits for uniting telephone lines, cut-off or line signal-effacing relays, said cut-off relays in establishing their alternative circuits opening their previously established circuits, circuit connections for the cord circuit plugs, whereby circuits through said cut-off relays may be momentarily closed, alternative circuits for said cut-off relays established thereby, line relays entering into the control of the latter circuits, line signal devices, and circuits therefor establishable by the line relays and breakable by the cut-off relays. 90 95 100

12. A telephone exchange system including telephone lines extending to an exchange and there provided with jacks, cord circuits for uniting telephone lines, cut-off or line signal-extinguishing relays normally in circuit connection with jacks of the corresponding lines, circuit connections for the cord-circuit plugs, whereby circuits through said cut-off relays may be momentarily closed, alternative circuits for said cut-off relays established thereby, line relays entering into the control of the latter circuits, a battery for energizing said cut-off relays, said battery being normally disconnected from the cord circuits, line signal devices, and circuits therefor establishable by the line relays and breakable by the cut-off relays.

13. A telephone exchange system including telephone lines extending to an exchange and there provided with jacks, cord circuits for uniting telephone lines, cut-off or line signal-erasing relays, circuit connections for the cord circuit plugs, whereby circuits through said cut-off relays may be momentarily closed, alternative circuits for said cut-off relays established thereby, line relays entering into the control of the latter circuits, a battery for energizing said cut-off relays, said battery being normally disconnected 130 120 125 130

from the cord circuits, line signal devices, and circuits therefor establishable by the line relays and breakable by the cut-off relays.

14. A telephone exchange system including telephone lines extending to an exchange and there provided with jacks; cord circuits for uniting telephone lines, cut-off or line signal-effacing relays normally in circuit connection with jacks of the corresponding line, 10 said cut-off relays in establishing their alternative circuits opening their previously established circuits, circuit connections for the cord circuit plugs, whereby circuits through said cut-off relays may be momentarily closed, alternative circuits for said cut-off relays established thereby, line relays entering into the control of the latter circuits, a battery for energizing said 15 cut-off relays, said battery being normally disconnected from the cord circuits, line signal devices, and circuits therefor establishable by the line relays and breakable by the cut-off relays.

15. A telephone exchange system including telephone lines extending to an exchange 20 the cord circuits, line signal devices, and circuits therefor establishable by the line relays and breakable by the cut-off relays.

and there provided with jacks, cord circuits 25 for uniting telephone lines, cut-off or line signal-effacing relays, said cut-off relays in establishing their alternative circuits opening their previously established circuits, circuit connections for the cord circuit plugs, 30 whereby circuits through said cut-off relays may be momentarily closed, alternative circuits for said cut-off relays established thereby, line relays entering into the control of the latter circuits, a battery for energizing said 35 cut-off relays, said battery being normally disconnected from the cord circuits, line signal devices, and circuits therefor establishable by the line relays and breakable by the cut-off relays.

In witness whereof, I hereunto subscribe my name this 26th day of September A. D., 40 1906.

ELMER R. CORWIN.
